UNITED STATES PATENT OFFICE.

CHARLES S. ROBBINS AND EDWARD B. COBURN, OF WORCESTER, MASSACHUSETTS.

SNOWPLOW.

Application filed June 17, 1924. Serial No. 720,577.

To all whom it may concern:

Be it known that we, CHARLES S. ROBBINS and EDWARD B. COBURN, both citizens of the United States, residing at Worcester, 5 in the county of Worcester and Commonwealth of Massachusetts, have invented a new and useful Improvement in a Snowplow, of which the following, together with the accompanying drawings, is a specification.

Our invention relates generally to snow plows and has particular reference to an improved snow plow for use in connection with motor vehicles of the heavy duty type, 15 such as trucks, busses and tractors.

The object of our invention is to provide a novel arrangement of one or more plows in connection with a suitable vehicle, whereby the street, or highways, may be readily 20 cleared of snow, the width of the path broken through the snow by our improved plows being capable of considerable variation by adjustment of the plows. Our invention further contemplates an improved 25 arrangement of plows, whereby the passage of the plows through the snow will cause the snow which has been previously pushed aside to be lifted from the street, or roadway, and be delivered on either side of the 30 vehicle above the level of the street, or roadway. The above and other advantageous features of our invention will hereinafter more fully appear, reference being had to the accompanying drawings in which

Fig. 1 is a plan view of a motor vehicle provided with snow plows embodying our invention.

Fig. 2 is a view in side elevation of the parts shown in Fig. 1.

Fig. 3 is a view in front elevation of the parts shown in Fig. 1.

Fig. 4 is a transverse sectional view along the line 4—4 through one of the plows shown in Fig. 1.

Fig. 5 is an enlarged detail view of the pivotal mounting for one of the side plows shown in Fig. 2.

Fig. 6 is a horizontal sectional view along the line 6—6 of Fig. 5.

Like reference characters refer to like parts in the different figures.

Referring first to Figs. 1 and 2, the outline of the frame of a motor vehicle is shown, the frame consisting generally of longitudinal side members 1, 1, extending the length of the vehicle. For purposes of illustration, the frame is shown as being that of a wheeled vehicle having front and rear axles 2 and 3 and wheels 4. It is to be understood, however, that our invention is capable of being applied to types of vehicles other than the one illustrated, such as tractors and busses.

As best shown in Fig. 1, our improved arrangement consists primarily of a plow 5 carried at the front of the frame, and wing plows 6, 6, pivotally secured to the sides of the frame. The front plow 5 consists of divergent side portions 7, 7, the apex, or prow of the plow 5 being located substantially at the center of the vehicle. The wing plows 6, 6, are preferably straight and are of the same general form as the side portions 7, 7, of the front plow 5, a typical cross section of the plow portions 6 and 7 being shown in Fig. 4. Each of the plow sections 6 and 7 are concave in form, the curvature of the plow sections being such as to insure that the snow will be pushed aside with a rolling action, as will be hereinafter described.

As best shown in Fig. 1, the plow 5 is provided with a cross rod, or brace 8, which extends between the side portions 7, 7, at points considerably removed from the apex of the plow 5, so that the plow as a whole, is a substantially rigid triangular structure. The cross brace 8 is pivotally supported by arms 9, 9, each of which is carried at its other end by a hanger 10, as best shown in Fig. 2. The hangers 10 are secured to fixed portions of the vehicle, such as the springs on which the frame is supported, or the hangers 10 may as well be secured to the axle 2, or any other conveniently located fixed portions of the vehicle. Each of the arms 9 is free to turn on a pivot pin 12 carried by the corresponding hanger 10.

The plow 5 is thus further supported by means of a bracket 13 which extends upwardly from beneath the frame and termi-

nates at a point above the plan center of the plow. The bracket 13 is generally yoke-shaped in form with its arms 14 pivotally mounted at their ends on the same pins 12 which carry the arms 9. A sleeve 15 is pivotally carried at the upper end of the bracket 13 on a pin 16, and a thrust rod 17 extends loosely through the sleeve 15. The thrust rod 17 extends downwardly into the plow 5 and its lower end is pivotally connected to the plow by means of a pin 18 carried by a lug 19 provided just in back of the apex of the plow 5. The thrust rod 17 is threaded along its upper portion to receive nuts 20 and 21 on either side of the sleeve 15, and springs 22 and 23 surround the portions of the rod 17 between the nuts 20 and 21 and the sleeve 15. With this arrangement, it is obvious that while the thrust rod 17 is normally maintained in a given position within the sleeve 15 by the springs 22 and 23, yet the rod 17 is capable of sliding within the sleeve 15 in response to pressure exerted on the plow 5, as will be hereinafter described.

The plow 5, together with its supporting arms 9 and bracket 13, is suspended from a yoke 24 by means of a rigging consisting of chains 25 extending from the three corners, or apexes of the plow, to a ring 26. The ring 26 in turn is suspended from the yoke 24 by means of blocks 27 with a chain 28 extending therebetween, whereby the position of the ring 26 may be adjusted with respect to the yoke 24. By means of this rigging, including the chains 25 and the blocks 27 and tackle, the complete plow 5 may be suspended at the desired position above the ground so as to control the amount of snow which is removed from the surface traversed by the plow. When the plow 5 is thus suspended from the yoke 24 by the chains 25 and the associated rigging, it will be apparent that while the plow 5 is positioned longitudinally on the vehicle by means of the arms 9 and the center bracket 13, yet the pivotal connection of the arms 9, both to the frame of the vehicle and to the cross rod 8 of the plow, will permit of ready vertical adjustment of the plow with respect to the ground.

Furthermore, the pivotal connection of the arms 9 and the bracket 13, together with the slideable mounting of the thrust rod 17, will permit the plow 5 to yield without damage when it encounters a solid, and relatively immovable obstruction in its progress over the ground. Obviously, should the plow 5 so yield, it will return to its original position when the obstruction has been passed over, by reason of the fact that it is suspended from the yoke 24. Furthermore, the action of the springs 22 and 23 on the thrust rod permits the prow of the plow to be closely adjusted with respect to the ground surface, so that the plow will always

return to this position whenever it may happen to yield, upon encountering an obstruction.

As previously stated, each of the wing plows 6 is pivotally mounted on the frame of the vehicle, and in carrying out our invention the wing plows 6 are so mounted as to be capable of pivotal movement about axes at right angles to each other. In other words, we provide what is in effect a universal mounting for each of the wing plows 6, whereby each plow is capable of adjustment about a vertical axis fixed with respect to the frame, and is also adapted for pivotal movement about a substantially horizontal axis, as will now be described.

As best shown in Figs. 5 and 6, the inner end of each wing plow 6 is provided with a bracket 29 having spaced lugs 30, through which extends a pivot pin 31, the axis X—X⁷⁰ of which lies in a substantially horizontal plane. A foot 32 is pivotally mounted on the pin 31 between the lugs 30 of the bracket 29 and this foot 32 provides a cylindrical portion 33 having an opening extending therethrough substantially at right angles to the axis X—X⁷⁵ of the pin 31. A shaft 34 extends through the portion 33 of the foot 32, and as best shown in Fig. 5, this shaft extends through a bearing 35 carried by the side member 1 of the frame, with its axis Y—Y⁸⁰ substantially vertical. The shaft 34 also extends through a bearing 36 carried by an auxiliary frame member 37, so that the shaft 34 is vertically aligned with respect to the frame.

The lower end of the shaft 34 is provided with an enlarged portion 38, and as the cylindrical portion 33 of the foot 32 which carries the wing plow 6, rests against the shaft portion 38, the shaft 34 carries the entire weight of the plow 6. The shaft 34, together with the plow 6, is supported by an inverted U-shaped bracket 39, and means are provided for adjusting the shaft 34 vertically with respect to this bracket 39. To this end, the shaft 34 is provided with an extension 40, the upper portion of which is threaded, as indicated at 41, and passes through an opening provided in the bracket 39. A nut 42 is received on the threaded portion 41, so that the nut 42 bears on the bracket 39 and maintains the shaft 34 and the wing plow 6 in its vertical position. The nut 42 is secured to a hand wheel 43, or other suitable operating portion, whereby the nut 42 may be turned on the threaded portion 41 in order to raise or lower the shaft 34 and the wing plow 6. The shaft 34 is provided with a keyway 44 which is adapted to receive the reduced end of a stud 45 extending through the wall of the bearing 36, whereby the shaft 34 is prevented from turning when the nut 42 is turned. The extension 40 of the shaft 34 which carries the nut 42 may

be either formed integrally with the shaft 34, or may be pinned or otherwise secured thereto for convenience of manufacture, as desired.

5 As previously stated, the shaft 34, together with its wing plow 6, may be raised or lowered by turning the nut 42, and in addition, we have provided separate means whereby the shaft 34 may be raised quickly 10 without turning the nut 42. For this purpose, the shaft 34 is provided with a fixed collar 46, to which is pivotally connected one end of a lever 47, by means of a pin 48. The lever 47 is pivotally mounted on one 15 leg of the bracket 39 by means of a pivot pin 49, and it is obvious that the shaft 34 and its wing plow 6 may be raised by depressing the longer portion of the lever 47 beyond its pivot pin 49. In this way the 20 shaft 34, carrying the wing plow 6, may be quickly raised in case of an emergency, by depressing the lever 47, but when the lever 47 is released, the shaft 34 will immediately drop to its former position, determined by 25 the position of the nut 42. It is to be understood that the lever 47 is only used when it is desired to raise the shaft 34 quickly, the nut 42 being relied on to ordinarily determine the vertical position of the shaft 34 and to make the adjustments of the position of the shaft and its associated wing 30 plow 6.

It is apparent from the foregoing description that each wing plow 6 is free to turn 35 about its horizontal pivot pin 31 at its inner end, and in order to maintain the outer end of each wing plow at the proper position, a chain 50 is connected thereto which is secured to a post 51 carried at the rear portion 40 of the frame member 1. Suitable means are provided for adjusting the length of each chain 50, so that the outer end of each plow 6 will be held at the proper position. In addition to being turnable about its horizontal pivot pin 31, each plow 6 is also turnable 45 about its vertical shaft 34, whereby the angle which a plow 6 makes with respect to the line of travel of the vehicle may be varied. In order to maintain each plow 6 at the desired inclination, a bar 52 is pivotally connected at one end to the free end 50 of each plow 6, and the other end of the bar 52 is secured by a holder 53 mounted at the end of a side frame member 1. Each bar 52 55 is provided with a number of spaced transverse openings 54 wide enough to receive a holder 53, whereby the bar 52 may be secured at different points, a pin 55 being provided to prevent the bar slipping off its holder. It is obvious that the positions of the bars 52 on the holders 53 will determine the inclination of the wing plows 6 with respect to the side members 1 of the frame, and that this inclination can be read-

ily varied by placing the holders 53 in different openings 54.

It will be apparent from an inspection of Figs. 1 and 2 that with our improved arrangement of the plows 5 and 6, it is possible to operate a vehicle carrying the plows 70 so as to cope with a wide variety of snow and road conditions. In the first place, the height that the front plow 5 is suspended above the road surface by the chains 25, determines the amount of snow that is left 75 on the surface of the road after the passage of the plow, while the width of the plow 5 determines the width of the path which is originally cleared in the snow. It is obvious that the width of the path which is made by the passage of the plow 5 can be increased by so adjusting the wing plows 6 as to project beyond the extremities of the front plow 5. With such a disposition of 80 the wing plows 6, the width of the path cleared by the front plow 5 will be considerably increased, and it follows that the adjustment afforded in the setting of the plows 6 enables the width of the path to be closely determined.

As previously mentioned, the plows 6 in addition to being swung in a horizontal plane, can also be set at different angles with respect to the road surface by reason of the provision of the horizontal pivots. The 90 angle which the lower edge of a plow 6 makes with the surface of the road is determined by the length of its supporting chain 50, and the plows 6 are shown as having been upwardly inclined in Fig. 3. With the plows 6 thus inclined with respect to the road surface, progress of the vehicle results in both pushing aside and lifting of the snow by the wing plows 6. The lifting of the snow results from the rolling action 100 which is imparted to the snow by the curvature of both plows 5 and 6, as shown in Fig. 4, so that when the plows 6 encounter the snow which has been already pushed aside by the plow 5, the snow will be elevated by 105 engagement with the inclined surfaces of the plows 6. This action is indicated in curved lines in Fig. 3, from which it will be apparent that the plows 6 may be utilized to effectively plow a roadway which has 110 already been plowed, and on which are banks 115 of snow extending on either side of the front plow.

When such banks of snow are already 120 present along the sides of a road, it is obvious that a vehicle provided with only a front plow would encounter very great resistance to its progress, by reason of the tendency of the fresh snow to pack against the banked snow, which of course, has a 125 greater density than the fresh snow. When the vehicle is provided with wing plows 6, disposed at an angle to the surface of the

roadway, it is obvious that the fresh snow which is pushed aside by the front plow 5 will be elevated by the wing plows 6 as the vehicle progresses, thus lifting the freshly 10 plowed snow clear of the snow banks which extend on either side of the road. When the freshly plowed snow is lifted clear of the side banks, resistance to movement of the vehicle is materially reduced, and in fact 15 will not be very much greater than the resistance encountered in plowing freshly laid snow for the first time.

From the foregoing, it is apparent that by our invention we have provided an improved 20 arrangement of snow plows for use in connection with motor vehicles of the heavy duty type, our arrangement of plows making it possible to plow a pathway of almost any desired width and depth, and as many 25 times as may be desired during the course of a winter. While we have shown our plows in connection with a vehicle of a particular type, it is obvious that it is not so limited, but may as well be employed in connection 30 with other types of vehicles without departing from the spirit and scope of our invention.

We claim,

1. In apparatus for removing snow, a vehicle, a wing plow pivotally attached at its front end to said vehicle for movement about a vertical axis, the full weight of said front end of said plow being carried by said vehicle, said plow being further pivotally 35 mounted at substantially the same place for movement about a horizontal axis, said plow being held rigidly about its own longest dimension as an axis, and adjustable means at substantially the rear end of said plow 40 holding it outwardly from said vehicle.

2. In apparatus for removing snow, a vehicle, a wing plow pivotally attached at its front end to said vehicle, for movement about a vertical axis, the full weight of said 45 front end of said plow being carried by said vehicle, said plow being further pivotally mounted at substantially the same place for movement about a horizontal axis, said plow being held rigidly about its own longest 50 dimension as an axis, adjustable means at substantially the rear end of said plow holding it outwardly from said vehicle, and further adjustable means supporting the weight 55 of the rear end of said plow from said vehicle, allowing said plow to normally rest by its own weight at a predetermined angle to the horizontal surface of the ground.

3. In apparatus for removing snow, a vehicle, a substantially vertical shaft carried by said vehicle, a wing plow, a pivotal connection between the front end of said plow and said shaft, said connection allowing swinging movement of said plow about a vertical axis and allowing pivotal movement of said plow about a horizontal axis

substantially perpendicular to its longest dimension, and holding said plow rigid about its longest dimension as an axis, means including said shaft and a flexible connection adjacent the rear end of said plow 70 holding said plow suspended from said vehicle at any desired angle and height, said means allowing either or both ends of said plow to raise upon the encountering of an unplowable obstruction, and adjustable 75 means holding the rear end of said plow spaced from the rear of said vehicle.

4. In apparatus for removing snow, a vehicle, a substantially vertical shaft carried by said vehicle, a wing plow, a pivotal connection between the front end of said plow and said shaft, said connection allowing swinging movement of said plow about a vertical axis and allowing pivotal movement of said plow about a horizontal axis substantially perpendicular to its longest dimension, and holding said plow rigid about its longest dimension as an axis, means including said shaft and a flexible connection 80 adjacent the rear end of said plow holding said plow suspended from said vehicle at any desired angle and height, said means allowing either or both ends of said plow to raise upon the encountering of an unplowable obstruction, adjustable means 85 holding the rear end of said plow spaced from the rear of said vehicle and lever means to quickly raise the front end of said plow.

5. In apparatus of the class described, a vehicle frame, a shaft vertically mounted for sliding movement on said frame, a plow, means attaching said plow to said shaft, allowing said plow to swing about the axis of said shaft, and screw mechanism for 90 raising and lowering said shaft.

6. In apparatus of the class described, a vehicle frame, a shaft vertically mounted for sliding movement on said frame, a plow, means attaching said plow to said shaft, 100 allowing said plow to swing about the axis of said shaft, a hand wheel and screw mechanism operated thereby for raising and lowering said shaft.

7. In apparatus of the class described, a vehicle frame, a bracket attached to said frame, a vertical shaft passing through said bracket, a plow mounted to swing about the axis of said shaft as a pivot, screw threads on said shaft, and means including a hand wheel adapted to cooperate with said threads to raise said plow.

8. In apparatus of the class described, a vehicle frame, a vertical shaft slidably carried by said frame, a plow carried by said shaft adapted for swinging about said shaft as an axis, and lever mechanism to raise said shaft.

9. In apparatus of the class described, a vehicle frame, a vertical shaft slidably car-

ried by said frame, a plow carried by said shaft adapted for swinging about said shaft as an axis, a collar on said shaft, a lever operatively engaging said collar and pivotally carried by said frame, thereby when actuated to raise said shaft.

10. In apparatus of the class described, a vehicle frame, a vertical shaft slidably carried by said frame, a plow carried by

said shaft adapted to swing about said shaft 10 as an axis, screw threads on said shaft, means including a hand wheel adapted to cooperate with said threads to raise said plow, and further lever means adapted when actuated to raise said plow more quickly. 15

Dated this tenth day of June, 1924.

CHARLES S. ROBBINS.

EDWARD B. COBURN.
